UNITED STATES PATENT OFFICE.

EDWARD CLIFFORD WADSWORTH, OF BROOKLYN, NEW YORK.

DESIGN FOR A BOTTLE.

SPECIFICATION forming part of Design No. 16,200, dated August 11, 1885.

Application filed June 21, 1885. Term of patent 7 years.

To all whom it may concern:

Be it known that I, E. CLIFFORD WADSWORTH, a citizen of the United States, residing at Brooklyn, in the county of Kings and State of New York, have invented certain new and useful Designs for Bottles; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a representation of this invention, and is a perspective view. Fig. 2 is a top view. Fig. 3 is a front view. Fig. 4 is a transverse sectional view taken on the lines $x x$ of Fig. 3.

This design is for a bottle; and it consists in the novel configuration and form of the bottle, as hereinafter shown and described.

The leading feature of my design consists in forming on an enlarged body, having circular sides surrounded with a flange, a neck having a rectangular mouth and connected with the body by inward vertical curves.

In the accompanying drawings the bottle is represented having a mouth of rectangular elongated form. The neck connects with the 30 enlarged body. The base A is formed with opposite flanges, which are beveled on their outer edges. The front and rear of the body is represented as circular convex, and the said convex back and front are surrounded by a 35 flange, D, which rises from the flat base at the inner portions of the flanges A.

Having described this design, what I claim is—

The design for bottles, having the neck connected with the enlarged body by inward vertical curves, the base having beveled flanges extending from the lower end of the body curves, the back and front of the body being circular convex, and having surrounding 45 flanges rising from the base at the inner ends of its beveled flanges, substantially as shown and described.

In testimony whereof I affix my signature in presence of two witnesses.

EDWARD CLIFFORD WADSWORTH.
